UNITED STATES PATENT OFFICE.

WILLIAM BLACKBURN AND SAMUEL BLACKBURN, OF CLECKHEATON,
COUNTY OF YORK, ENGLAND.

TIGHTENER FOR SPINDLE-BANDS OF SPINNING-MACHINES.

SPECIFICATION forming part of Letters Patent No. 356,239, dated January 18, 1867.

Application filed May 13, 1866. Serial No. 202,069. (No model.) Patented in England March 20, 1885, No. 3,605.

To all whom it may concern:

Be it known that we, WILLIAM BLACKBURN and SAMUEL BLACKBURN, subjects of the Queen of Great Britain, residing at Cleckheaton, in the county of York, England, have invented new and useful Improvements in Tighteners for Spindle-Bands of Spinning-Machines, (for which we obtained a patent in Great Britain, No. 3,605, March 20, 1885,) of to which the following is a specification.

The object of this invention is to give a long traverse and so use long bobbins; also, to insure a regular twist in spinning and twisting fibers, and to take up the bands automatically as the tubes of the spindles rise and fall; also, to deliver the bands onto the whirls in a direct straight line. We attain these objects by mechanism illustrated in the accompanying drawings, in which—

20 Figure 1 shows a portion of a spinning-frame in elevation and partly in section with our improvements attached. Figs. 2 and 3 show details of self-lubricating pulleys.

We employ two loose pulleys, A A, for each 25 spindle B, between the tin cylinder D and the whirls E, the bands running under and over the pulleys, respectively. Each set of the pulleys is carried by a forked lever, F, which is pivoted on a second pivoted lever, H, which 30 is carried by a bar or rail, J. The other end of the fork-lever, F, carries a compensating-weight, C, adjustable by the slot K and screw G, and acting automatically to regulate the balance of the fork and pulleys. The other end

of the second pivoted lever, H, is formed with 3; a balance-weight at its end M, acting automatically when the lifter-rail I and tube of the spindle are in the center of their lift. The pulleys A take up the slack of the bands R, when moved nearer the tin cylinder D, by 40 means of the second pivoted lever, H. When a band breaks the lever H moves forward by reason of its weighted end M, as shown in dotted lines, and is prevented from coming in contact with the cylinder by pressure of the 45 flat bar J within a notch, L, formed in said lever.

The pulleys A A are self-lubricating, the studs N being hollow and split or perforated, and contain a fibrous material, P, which is 50 saturated with lubricant. The fork and pulleys may be pivoted on a shaft, if preferred.

What we claim as the invention, and desire to secure by Letters Patent, is—

The combination of the spindles B B, cylinder D, bands R, rails J J, the weighted levers H H, engaging said rails, the forked levers F F, pivoted on the levers H H and provided with adjustable weights C C, and the pulleys A A, carried by the levers F F, substantially 55 60 as described.

WM. BLACKBURN.
SAML. BLACKBURN.
